UNITED STATES PATENT OFFICE

CHARLES S. HAZARD, OF FLUSHING, NEW YORK, N. Y., ASSIGNOR TO NEPTUNE METER COMPANY, OF NEW YORK, N. Y., A CORPORATION OF NEW JERSEY

DESIGN FOR METER HOUSING

Application filed September 11, 1930. Serial No. 36,934. Term of patent 7 years

To all whom it may concern:

Be it known that I, CHARLES S. HAZARD, a citizen of the United States, residing in Flushing, in the county of Queens of the city of New York, in the State of New York have invented a new, original, and ornamental Design for Meter Housing, of which the following is a specification, reference being had to the accompanying drawings, forming a part hereof.

Figure 1 is a plan view of a meter housing showing my new design.

Figure 2 is a view in side elevation.

Figure 3 is a view in rear elevation.

I claim:

The ornamental design for a meter housing, as shown.

This specification signed this 5th day of Sept., A. D. 1930.

CHARLES S. HAZARD.
